DESIGN FOR A COMBINED AIR CLEANER AND REGULATOR

Glenn W. Tammen, Chicago, Ill., assignor to Binks
Manufacturing Company, Chicago, Ill., a cor-
poration of Delaware

Application September 19, 1941, Serial No. 103,411

Term of patent 7 years

To all whom it may concern:

Be it known that I, Glenn W. Tammen, a citizen of the United States, and residing at Chicago, county of Cook, and State of Illinois, have invented a new, original, and ornamental Design for a Combined Air Cleaner and Regulator, of which the following is a specification, reference being made to the accompanying drawings, forming a part thereof.

Fig. 1 is a front elevational view of a combined

air cleaner and regulator showing my new design;

Fig. 2 is a side elevational view thereof;
Fig. 3 is a rear elevational view thereof; and,
Fig. 4 is a top plan view thereof.

I claim:

The ornamental design for a combined air cleaner and regulator, substantially as shown.

GLENN W. TAMMEN.
